UNITED STATES PATENT OFFICE.

HYMAN LEVINE, OF DENVER, COLORADO, ASSIGNOR TO INGERSOLL-RAND COMPANY,
OF JERSEY CITY, NEW JERSEY, A CORPORATION OF NEW JERSEY.

ENGINE.

Application filed November 27, 1925. Serial No. 71,807.

To all whom it may concern:

Be it known that I, HYMAN LEVINE, a citizen of the United States, and a resident of Denver, in the county of Denver and State of Colorado, have invented a certain Engine, of which the following is a specification, accompanied by drawings.

This invention relates to engines and more particularly to that type of engine in which there is provided a reciprocating piston and a rotary piston therewithin to transmit power to a crank pin. More particularly, this invention relates to arrangement of ports and passages in the cylinder heads and the rotary piston for distributing motive fluid to the pressure faces of the piston and to educt the exhaust fluid therefrom.

One object of the invention is to eliminate restrictions in the ports and passages of the rotary piston in this type of engine. Another object of the invention is to provide large exhaust port area to minimize back pressure in the engine. Another object is to cut off the inlet to use air expansively. Still other objects of the invention are to reduce the volumetric clearance by closing exhaust ports before end of stroke causing compression in the clearance space and to provide a direct path for the exhaust fluid to atmosphere. Other objects of the invention are to provide space for crank bearings and to permit the crank bearing to be placed centrally in the rotary piston.

The invention will be more clearly understood by reference to the drawings, in which similar characters refer to similar parts, and in which—

Figure 1 is a cross sectional view of the invention, the ports being shown diagrammatically,

Figure 2 is a longitudinal section of the invention along the line 2—2 looking in the direction of the arrows,

Figure 3 is a diagrammatic representation showing the cooperation of the ports, the reciprocating piston being shown at the beginning of its power stroke,

Figure 4 is a diagrammatic representation of the engine showing the reciprocating piston at the point of cut off of motive fluid,

Figure 5 is a diagrammatic representation of the engine showing the reciprocating pis-

ton at the end of its power stroke and the exhaust port opening,

Figure 6 is a diagrammatic representation of the engine showing the reciprocating piston on its return stroke, the exhaust port being open, and

Figure 7 is a diagrammatic representation of the engine showing the piston near the end of its exhaust stroke producing compression in the clearance space prior to admission of motive fluid.

Referring to the drawings, the engine comprises a cylinder A having a front head B and back head C bolted to the cylinder A by means of suitable bolts D. Within the cylinder A there is provided a frame piston E having an inner rotary piston F rotatably secured as by means of a suitable bearing G to a crank pin H of the drive shaft J. The rotary piston F is provided with two flat faces K which are guided by and slide in corresponding inner faces L of the reciprocating piston E. As is seen by referring to Figure 1, the frame piston E and the rotary piston F reciprocate at right angles with respect to each other and the motion imparted by the frame piston E to the rotary piston F in combination with the reciprocating movement of the rotary piston F are resolved into a rotary motion of the crank pin H as is well known in connection with engines of this type.

The rotary piston F acts as a valve for distributing motive fluid to the end faces of the frame piston and rotary piston and for controlling the exhaust of motive fluid therefrom to atmosphere. To this end there are provided a set of ports O extending through the piston F from the face adjacent the front cylinder head B into passages P leading directly to the end faces of the reciprocating frame piston E and the rotary piston F. The passages P are short and of just sufficient cross section area to conduct motive fluid without substantial loss and also to provide a minimum clearance volume. The ports O are preferably relatively close to the end faces of the pistons with which they communicate. In order to supply motive fluid to the ports O a set of ports Q are provided in the front cylinder head B corresponding to the ports O and connected together by a common chamber R

in the cylinder head B. Motive fluid is admitted to the chamber R at an aperture S threaded to receive a suitable pipe T. As the piston F rotates the ports O register successively with the ports Q to admit motive fluid into the cylinder A. For exhausting motive fluid from the engine there are provided a set of elongated ports U corresponding to the ports O and adapted to register therewith leading to atmosphere. The ports U are located in the front cylinder head B and communicate with a common chamber V separated from the chamber R by a wall W. A threaded aperture X is provided in the chamber V and is adapted to be connected with a suitable threaded pipe Y to conduct the exhaust to any suitable point.

In order to reduce back pressure in the cylinder A on the return stroke of the pistons E and F, auxiliary exhaust ports b are provided in the rear cylinder head C opening into a chamber d leading to atmosphere through an aperture e. A corresponding set of ports f are provided in the face of the piston F adjacent the rear cylinder head C and are adapted to register with the ports b at the same time that the ports O register with the exhaust ports U.

The inlet ports Q are spaced from the exhaust ports U laterally a distance determined by the degree of cut off desired thus as shown in Figure 1 the ports O pass the inlet ports Q at from 50% to 75% of the stroke and the exhaust ports U are not open to the ports O until the end of the stroke which allows expansion of motive fluid at the end of the power stroke.

The operation of the engine is shown more clearly in Figures 3, 4, 5 and 6 in which only the ports corresponding to one face of the frame piston E are shown. The path of the center of the crank pin H is shown as a circle g, the center of which is the center of rotation of the rotary piston F.

In Figure 3, the frame piston E is shown at the beginning of the power stroke at which point the distributing port O in the frame piston is shown just coming into registry with the inlet port Q in the cylinder head B. Motive fluid is being permitted to enter the port Q and thence through the passage P to the end face of the frame piston E forcing the frame piston downwardly on its power stroke. As the inner piston F rotates in the direction of the arrow up to a point from 50% to 75% from the beginning of the stroke, the port O passes by the inlet port Q shutting off the supply of motive fluid to the end face of the frame piston E and permitting the motive fluid in the cylinder to expand for the remainder of the stroke. At the end of the stroke the distributing port O begins to register with the exhaust port U permitting the exhaust to pass

out through the chamber B to atmosphere as shown in Figure 6. Simultaneously the auxiliary exhaust port f registers with the exhaust port b in the cylinder head C permitting the escape of exhaust motive fluid into the chamber d and thence to atmosphere through the aperture e. Figure 5 shows more clearly the distance traveled by the distributing port O in the piston F after passing the inlet port Q to utilize the expansion of motive fluid in the cylinder. Near the end of the exhaust stroke the exhaust ports b and U close as shown in Figure 7 to compress the residual fluid in the cylinder producing a cushion and economizing in the amount of motive fluid to be admitted on opening of the inlet port Q.

In Figures 3, 4, 5, 6 and 7 only those ports are shown which are about to register the remaining ports being omitted for the sake of clearness.

I claim:

1. An engine comprising a cylinder having front and rear heads, a reciprocating frame piston within said cylinder, a rotary piston within said frame piston, a port in said rotary piston for each end face of the frame and rotary pistons, a set of inlet ports in the front head of said cylinder corresponding to said ports in the rotary piston, a set of exhaust ports spaced from the set of inlet ports to cooperate with said ports in the rotary piston, and additional exhaust ports in the rear face of said rotary piston and the rear cylinder head for exhausting motive fluid from the engine.

2. An engine comprising a cylinder having front and rear heads, a reciprocating frame piston within said cylinder, a rotary piston within said frame piston, a set of ports in said rotary piston leading to the end faces of said reciprocating and rotary pistons, a set of inlet ports in the front cylinder head corresponding to said ports in the rotary piston, a set of exhaust ports in the front cylinder head corresponding to the set of ports in the rotary piston and laterally spaced therefrom, and a set of auxiliary exhaust ports in the rear face of said rotary piston in communication with the end faces of the reciprocating and rotary piston, and a set of exhaust ports in the rear cylinder head adapted to cooperate with the auxiliary exhaust ports in the rotary piston and simultaneously therewith.

3. An engine comprising a cylinder having front and rear heads, a reciprocating frame piston within said cylinder, a rotary piston within said frame piston, a set of ports in said rotary piston leading to the end faces of said reciprocating and rotary pistons, a set of inlet ports in the front cylinder head corresponding to said ports in the rotary piston, a set of exhaust ports in the front cylinder head corresponding to

the set of ports in the rotary piston and laterally spaced therefrom, and a set of auxiliary exhaust ports in the rear face of said rotary piston in communication with the end 5 faces of the reciprocating and rotary piston, and a set of exhaust ports in the rear cylinder head adapted to cooperate with the auxiliary exhaust ports in the rotary piston

and simultaneously therewith, said exhaust ports being adapted to be closed before the 10 end of the stroke to produce compression in the clearance space of the cylinder.

In testimony whereof I have signed this specification.

HYMAN LEVINE.
